UNITED STATES PATENT OFFICE

WALTER B. CRAIGHEAD, OF ST. PAUL, MINNESOTA

BALL GAME

Application filed January 2, 1930. Serial No. 417,883.

My invention relates to game devices in general and more particularly to a baseball game device involving certain electric signal or display means so manipulated and operated as to simulate a real game of baseball. The players need no practice to play the game, a knowledge of the game as played by regulation teams, however, being necessary.

The object of the invention is to provide a baseball game device of such construction and use that the contestants may play a regulation baseball game of nine or more innings by the use of a common steel ball, the rolling of which causes successive plays to be made in such a way as to imitate a real ball game and the successive plays being entirely unknown previous to dropping the ball into the machine. Further objects and the playing of my game device are hereinafter fully set forth, reference being had to the accompanying drawings, in which,—

Fig. 1 is a top view of my improved baseball game device connected to an electric service socket in a wall and in position to be played.

Fig. 2 is a front end elevation of Fig. 1.

Fig. 3 is a schematic top view showing a limited number of electric circuit closing means used during the playing of the game.

Fig. 4 is a longitudinal sectional elevation as on line 4-4 in Fig. 1 omitting the electric circuits.

Referring to the drawings by reference numerals and letters, my device preferably of box-like construction, but bottomless, having a low front wall 5, higher side walls 6, a rear wall 7, a removable cover 8 preferably retained between the side and rear walls, and 9 is an angular, fixed front panel extending forward and downward between the side walls to the top of the front wall 5. The box described may be elevated from a floor or table surface 10 by corner props or legs 11.

The cover 8 as stated is removable, being fixed on spacer supports 12 (see Fig. 4), secured to a fixed plate 13 between the side walls 6 and under the plate 8. The cover 8 may be painted with a main field of green on which is painted in contrasting colors the runways comprising a baseball diamond and other markings as hereinafter described, said

diamond being designated D in Fig. 1. The cover 8 is a plurality of openings 14, singly and in groups in predetermined places designating players' positions and plays according to location of a baseball as determined step by step in the playing of the game. In each aperture 14 is an electric bulb 15 removably fixed in a socket 16 fixed to plate 13 and all in electric circuit means and illuminated at certain times by circuit closing means hereinafter described. Said bulbs are colored in predetermined positions, that is, some are green, some red and some white or yellow.

To facilitate description the various positions of apertures 14 on plate 8 are designated by letters, or combinations of letters or letters and numerals. Thus HP means home plate, 1B is first base, 2B second base, 3B third base, FL foul line, RF right field, CF center field, LF left field, and SS short stop, all in correct relative positions corresponding to a regulation baseball field approximately and readily understood by any person familiar with baseball games and fields. At each of the three base positions 1B, 2B and 3B are three apertures 14, one with a green bulb, one with a red bulb and one with a white bulb.

The front part of cover 8 is shown provided with a hole 17 through which a metal ball 18 is dropped to make a play in the process of playing a baseball game, said ball dropping on the upper part of a rearwardly and downwardly inclined fixed floor 19 on which the ball rolls toward the rear part of the box and is of course out of sight and its course unknown until it rolls off of the rear edge of floor 19 into one of a series of pockets P fixed to rear wall 7, said pockets comprising a series of vertical parallel walls 20 spaced equidistant along the entire rear part of the box, all said walls having lower edges in a common rearwardly and downwardly directed plane normally closed by a hinged metal plate 21 hinged at its upper edge on a pin or bar 22, journaled in the side walls 6 (see Fig. 3). Said hinge plate is energized by wire connection 23 to a battery 24 (Fig. 3) or through cable 23C to an electric wall socket 25. In the rear part of each pocket P is fixed a downwardly direct-

ed metal contact plate 26 also in electric circuit with wire 27, the lower edge of each contact plate or tongue 26 being in spaced relation but close to the lower free edge of the hinge plate 21. It will be readily seen that when the ball 18 rolls into any of the pockets P it closes circuit between plates 21 and 26 of said pocket lighting up a certain bulb for each said pocket. Certain plays will 10 presently be described to illustrate the procedure in playing a baseball game.

28 is a circuit opening reach rod mounted longitudinally and slidably within the box and protruding from the front part thereof 15 in a handle 28H, the inner end of said rod pivotally connected at 29 to the hinge plate 21.

30 is a coil spring about rod 28 between a fixed bracket 31 and a collar 32 on the rod, under compression, and normally but yieldingly pressing rod 28 rearward and holding plate 21 in pocket-closing forward position, it being understood that plate 21 closes all the pockets P simultaneously. A pull on handle 28H rocks plate 21 allowing ball 18 to drop onto a return plate 33 fixed in the lower part of the box and inclined forwardly where it terminates in upwardly opening pocket 33P in which the ball stops and is 20 accessible for further use.

In Figs. 1 and 2, 34 is a panel on plate 9 adapted to receive a baseball score card 35 on which may be recorded the various plays, runs, final scores, etc., made during the playing of the game, a complete game being designated on the card shown in Fig. 1.

35A in Figs. 1 and 2 shows a multiple switch plate having three independent switches 36A, 36B and 36C all in circuit and 40 connected via circuit wires, as 37 in Fig. 3, respectively to the red bulbs 15 in the base positions 1B, 2B and 3B, one such bulb in Fig. 3 being designated 15R in Fig. 3 and 1 and in circuit.

45 To illustrate the procedure in playing the game it will be assumed that one contestant drops a ball 18 into the device and said ball rolls into a circuit-closing pocket designated P3 in Fig. 3. Circuit is closed through wire 27 through light at LF (left field in Fig. 1) and simultaneously to white light designated 15W, indicating that a player hit to left field and ran to second base on the hit.

55 To record position of the imaginary player the contestant closes switch 36B which illuminates the red bulb 15R at second base position (2B) circuit being closed through wires 37 (see Fig. 3). Then the ball is released and 60 the white lights at LF and 2B are extinguished but the red light at 2B remains on. The group of bulbs 15X in lower right part of the field (Fig. 1) may be in circuit to signal successive strikes, balls or outs of imaginary players listed on the score card.

Obviously the switches 36A, 36B and 36C are manipulated to designate the positions of various imaginary players on the bases. In Fig. 1 the bulb designated FB indicates a foul-ball or the bulbs at FL indicate a so called foul-ball to right or left past the 1B or 3B positions.

In Fig. 3 the pocket P2 when circuit is closed therethrough by the ball causes RF bulb 15 to be illuminated and simultaneously 75 a bulb 15G at 1B position also illuminated which may indicate the imaginary player struck the ball to right field but was out at first base.

It is now clear that almost every conceivable kind of play in baseball can be designated during the playing of this game. The 80 number and kinds of plays are only limited by the number of circuit closing pockets 21 and it is also clear that the progress of the 85 game simulates the progress of a real baseball game and holds the interest of the players at all times. Full nine inning games may be played, the players using the ball 18 alternately for the respective teams they choose 90 to represent, for example, imaginary teams representing towns designated as Yorktown and Newburg on the score card 35 in Fig. 1.

In actual use this game device has sometimes worked so as to play tie-games of more 95 than nine innings or long games terminating in very close scores of one or two run margins.

An attractive feature in this game is its 100 uncertainty as will be readily understood because a contestant after each drop of the ball 18 does not know what the next play will be until the ball closes circuit in any one of the pockets B and causes illumination of one or more bulbs positively unknown in 105 advance because the course of the ball down the incline 19 can not be observed.

This game device is primarily intended 110 to be designed for playing a game simulating a baseball game but it is obvious that the playing field 8 and the positions designated by the bulbs of various colors and in various positions may be designed to simulate other games or entirely new games but in all of them the principles of construction 115 and the operation are such as have been fully described herein. In other words the circuit closing and opening means are herein embodied in principle but the games played may be varied and details of construction 120 considerably varied without departing from the scope and spirit of my invention.

I claim:

1. A game device of the class described 125 comprising a box-like cabinet with a horizontal upper plate, the surface of which is designed in simulation of a playing field, said plate provided with a predetermined number of apertures, a secondary plate under said first plate and a number of electric bulbs, in 130

circuit, mounted thereon each to be exposed in one of said apertures, a source of electric current, a plurality of circuit closing pockets each with a circuit closing member connected to certain of said bulbs, a hinged common circuit closing member in circuit and pivotally mounted on an axis parallel relation to said circuit closing means in the pockets, all said latter means being in an upright common plane and the common circuit closing device comprising a plate extending normally in inclined position toward said first members but spaced therefrom in V-formation, an inclined fixed plane within the box with its lower edge above said hinged circuit plate and its other edge fixed in the forward part of the box under the secondary plate, said upper plate provided with an aperture to drop a metal ball through and onto said inclined plane, said ball adapted to close circuit in any of said pockets when gravitating thereto and cause illumination of a bulb or bulbs as the case may be, and retrieving means adapted to release said ball from circuit closing position.

2. The structure specified in claim 1 and a secondary group of bulbs and apertures provided therefor in the top plate, independent circuit control means for said latter bulbs to register certain plays designated on the playing field.

3. The structure specified in claim 1 in which said ball retrieving means comprises an inclined plane in the device directed downwardly from a plane below said circuit closing pockets and terminating in a pocket accessible at the lower front part of the device.

4. The structure specified in claim 1 in which said ball retrieving means comprises an inclined plane in the device directed downwardly from a plane below said circuit closing pockets and terminating in a pocket accessible at the lower front part of the device, and spring means actuating said common circuit closing plate normally to position toward the alined circuit closing means in said pockets, a retracting rod connected to said plate and extending through the cabinet forwardly and projecting outwardly thereof, said rod adapted to be pulled to rock said circuit plate away from the fixed circuit members and pockets for the purpose set forth.

5. The structure specified in claim 1 in which said cabinet is formed with a front panel in an inclined plane, and score indicating means on said panel.

In testimony whereof I affix my signature.

WALTER B. CRAIGHEAD.
